No. 37,279.

Patented December 27, 1904.

UNITED STATES PATENT OFFICE.

DAVID L. TSCHANTZ, OF CANTON, OHIO.

DESIGN FOR A SURREY-BODY.

SPECIFICATION forming part of Design No. 37,279, dated December 27, 1904.

Application filed October 7, 1904. Serial No. 227,614. Term of patent 7 years.

To all whom it may concern:

Be it known that I, DAVID L. TSCHANTZ, a citizen of the United States, residing at Canton, in the county of Stark and State of Ohio, 5 have invented a new, original, and ornamental Design for a Surrey-Body, of which the following is a specification, reference being had to the accompanying drawing, forming part thereof.

o The figure is a left, rear, and slightly under perspective view of the surrey-body.

What I claim as new, and desire to secure by Letters Patent, is—

The ornamental design for a surrey-body, as shown.

DAVID L. TSCHANTZ.
